CYLINDRICAL CUTTER HEAD WITH SLOTTED BLADE SEAT

James S. Ballantine, Absecon, N. J.

Application May 17, 1949, Serial No. 93,701

2 Claims. (Cl. 144—230)

This invention relates to rotary cutter heads of the type employed in jointers, planers and similar wood-working tools and more particularly to improved mounting and holding devices for the bits or cutter blades of rotary cutter heads.

A primary object of the invention is the provision of improved adjusting and holding devices for the bits or cutter blades of a rotary cutter head wherein the bits or blades may be adjusted to a desired cutting position and then quickly and easily secured in such position by a simple manipulative procedure.

Another object of the invention is the provision of improved holding devices for the cutter blades of rotary cutter heads which may be quickly and easily released from locking position.

A further object of the invention is to secure a cutter blade in a recess of converging cross-section in a rotary cutter head by a locking bar through wedging or clamping engagement of one side of the bar with a side wall of the recess limited to substantially line engagement lengthwise of such sides. A related object of the invention is to differentially shape the coacting sides of the recess and bar and through such shaping limit their engagement to substantially line engagement.

Other objects and advantages of the invention will become more apparent in connection with the following description of preferred embodiments of the invention illustrated in the accompanying drawings.

In the drawings:

Fig. 1 is a view in side elevation of a rotary cutter head embodying one form of the invention;

Fig. 2 is an enlarged view in side elevation of a portion of the cutter head shown in Fig. 1;

Fig. 3 is an enlarged view similar to Fig. 2 with the cutter blade, locking bar, and adjusting screw omitted from the lower slot;

Fig. 4 is a cross-sectional view taken on the line 4—4 of Fig. 2;

Fig. 5 is a perspective view of the locking bar;

Fig. 6 is a vertical cross-sectional view of the locking bar;

Fig. 7 is a vertical cross-sectional view of a modified form of locking bar; and,

Fig. 8 is a vertical cross-sectional view of a further modified form of locking bar.

In general the present invention is directed to novel means for removably securing the cutter blades of a cutter head in place. The securing means includes a locking bar. The locking bar together with the cutter blade is fitted in a recess of outwardly converging cross-section in the cutter head.

The cutter blade will be disposed with one side against one side of the recess. The locking bar will be removably located between the blade and the opposite side of the recess. The bar should be of a cross-section to be loose in the inner wider portion of the outwardly converging recess but movable outwardly as a wedge into bearing engagement at its opposite sides with the cutter blade and one side of the recess.

The coacting sides of the recess and locking bar are limited to substantially line bearing engagement lengthwise thereof at an intermediate area of the bar when the bar is in wedging position. To this end such sides are differentially shaped so as to be spaced from each other above and below their line of engagement. One or the other of such sides must be contoured vertically, and both may be. I prefer to contour one only of the coacting sides and to make the other flat. I further prefer to contour the side of the locking bar and to make the coacting side of the recess flat and I have chosen various embodiments of such form of the invention for illustration in the drawings.

The opposite side of the locking bar is preferably flat

2

so as to make extended surface contact with the side of the cutter blade and wedge it securely against the second wall of the cutter head recess.

The shaping of the cutter head recess and locking bar as above explained to limit their sides to substantially line engagement insures increased wedging action and permits easier manipulation of the bar to and from wedging position than would be the case if the coacting sides of the recess and bar were both flat and in bearing engagement over an extended surface area.

While operation tests have shown that centrifugal force developed by rotation of the cutter is sufficient to maintain the wedging action of the locking bar it is desirable to provide means for positively holding the bar in wedging position and which also serves to adjust the bar from released to wedging position. Such means preferably will comprise a series of set screws threaded vertically in the locking bar which will bear at their inner ends against the bottom of the cutter blade recess and which upon turning will move the bar outwardly in the recess until it reaches wedging position.

Contouring to obtain the desired line contact between the sides of the locking bar and cutter blade recess may take a number of forms. According to one type of construction the side of the locking bar which engages a flat-formed side of the recess is formed with two angularly related upper and lower surfaces or faces which meet along a longitudinal line substantially midway between the top and bottom of the locking bar. The surface below the line may desirably be flat and is preferably substantially parallel to the opposite blade-engaging side so as to be downwardly divergent at a small acute angle with respect to the adjacent coacting side of the recess when the bar occupies its wedging position therein. The surface or face above the line is inclined inwardly toward the opposite side of the locking bar with a curved contour so that when occupying its normal position in the recess it will form a gradually increasing small acute angle with the adjacent side of the recess from the line of intersection with the lower surface.

In another but similar type of construction the recess coacting side of the locking bar is contoured to provide upper and lower surfaces or faces which are both flat and angularly related so as to meet along a longitudinal line and form small acute angles with the adjacent side, again flat, of the recess. In still another type of construction the side of the locking bar may continuously be curved for all or a substantial intermediate part of its height so that an intermediate curved portion is tangent to the adjacent side of the flat form of the recess and adapted to bearing engagement therewith substantially along a longitudinal line and the portions of the side above and below the tangent portion curve away from the adjacent face of the recess to form gradually increasing acute angles.

These and similar types of construction resulting in substantially line contact between the locking bar and the adjacent wall of the recess may be utilized in accordance with the present invention. The expression "line contact" as used herein is intended to mean contact along a line or area of very narrow width longitudinally of the locking bar as contrasted to extended surface contact between substantially parallel flat faces as hitherto used.

Referring now to the drawings and particularly to Figs. 1—4 the numeral 9 designates a cutter head of iron, steel, or the like, comprising a body member 10 which may be substantially cylindrical in shape and formed with a plurality of longitudinal recesses or channels 11 for the reception of cutting blades 12 and locking bars 13. 70 Any suitable number of recesses may be used, four being shown for the purpose of exemplifying the invention.

Each of the recesses 11 has a mouth 14 opening toward the periphery of the cutter head, opposite side walls 15 and 16 and a bottom wall 17. The side wall 15 forms a backing-face against which the impact of the blow exerted on the blade 12 in the cutting operation is received. The bottom wall 17 preferably extends at an acute angle with relation to the side wall 15 and is provided at one edge thereof with a groove 18 for the reception of the inner edge of blade 12. The side wall

16 is arranged in outwardly converging relationship with the side wall 15 to form a recess which is of tapering form in cross-section, wider at its bottom area than at its mouth.

Each of the locking bars 13 has a side face 20 adapted to be urged toward the blade, an opposite side face 21, a top face 22, and a bottom face 23. In operative position the side face 20 is substantially parallel to the back-face 15 of the recess 11 and is designed to wedge the blade in adjusted position as will be apparent from Fig. 4. The bottom face 23 is preferably, though not necessarily, arranged substantially at right angles to the side face 20 and at an acute angle to the bottom wall 17 of the recess 11. The top face 22 is preferably concavely curved or grooved as shown at 37 to provide a chip clearance and thereby increase the depth of cut of the machine.

The side face 21 of the locking bar is shaped so that the locking bar will have a wedge action within the walled recess 11. In accordance with the present invention this wedge action is along a single line of contact at the meeting of two angularly related upper and lower surfaces of the side face 21. This construction facilitates and increases the wedging action of the locking bar and additionally facilitates removal of the locking bar from its wedging position.

In the form of the invention shown in Figs. 1-6 the side face 21 is formed with two angularly related surfaces 24 and 25 which meet or intersect along a line 26 extending longitudinally of the bar. The surface 24 is preferably flat and may desirably be substantially parallel with the opposite side face 20. The surface 25 is preferably curved convexly inwardly toward the face 20 in such a manner that no portion of the curved surface above the line 26 is in contact with the side wall 16 of the recess 11 when the locking bar 13 is in wedging position. This construction provides an improved wedge action along a relatively narrow line of contact and simultaneously minimizes the possibility of particles of wood and the like working around the locking bar to disturb the wedging action.

In the modification of the invention shown in Fig. 7 the side face 21 is preferably formed with two intersecting flat faces 27 and 28 which meet in a line 29 extending longitudinally of the locking bar. The faces 27 and 28 are preferably arranged so that they form small acute angles with the side wall 16 of the recess 11 thus giving the desired line contact and minimizing the collection of foreign matter.

A further modification of the locking bar is shown in Fig. 8 wherein the line contact is obtained by a curved face 30 which is shaped so that a portion thereof is tangent to the wall 16 along a line longitudinally thereof. The curve of the face 30 may be varied as desired but is preferably arranged so as to recede gradually and to a relatively limited extent away from the face 16 above and below the line of contact.

In accordance with the present invention the line of contact of the locking bar with the adjacent wall of the recess is preferably located approximately midway between the upper and lower edges of the face 21 in order to obtain best all around results. Quite satisfactory results may be obtained, however, when the line of contact is above or below this location as long as the resultant of the forces acting on the blade through the line contact are sufficient to exert the desired clamping action.

The locking bars 13 are moved to and released from locking position by set-screws 31. Set-screws 31 are screw-threadedly mounted in openings 32 in the locking bars 13 and are preferably disposed substantially at right angles to the lower wall 17 of the recesses. The tops of the set-screws may be provided with suitable slots or the like for engagement by a screw driver, wrench or other suitable tool to rotate them. When it is desired to move the locking bars to locking position the set-screws 31 are rotated until they contact the bottom walls 17 of the recesses 11. Further rotation of the set-screws urges the locking bars upwardly in the tapering recesses 11 so that the line contact between the side faces 21 of the locking bars and the adjacent walls 16 of the recesses urges the faces 20 of the locking bars into tight engagement with the cutting blades 12. The blades 12 are thus clamped between the walls 15 of the recesses 11 and the

faces 20 of the locking bars 13 and securely held in position for the cutting operation.

Prior to being clamped in position as above described the cutting blades 12 are adjustably positioned for a desired cutting operation by nuts 33 screw-threadedly engaged with set-screws 34. Set-screws 34 are rotatably mounted in openings 35 in the cutter head 10 with the bottoms thereof resting in contact with the bottoms of the openings. The tops of the set-screws 34 may be provided with slots or the like whereby they may be rotated by a suitable tool to raise or lower the nuts 33. The nuts 33 are provided with extensions 33a which underlie the lower edges of the cutting blades 12 so as to support and move them upwardly or downwardly in response to rotation of the set-screws 34. The extensions 33a move upwardly and downwardly in openings 36 which are parallel to and communicate with openings 35. It will be apparent that when the set-screws 34 are rotated with the bottoms thereof in contact with the bottoms of the openings 35 the nuts 33 being screw-threadedly engaged therewith and held against rotation thereon are moved upwardly or downwardly to adjustably position the cutter blades 12. When the blades are thus adjusted to a desired cutting position the locking bars may then be moved to locking position as above described to securely hold the cutter blades in position.

It will thus be seen that the present invention provides an improved cutter head wherein the cutter blades may be easily, quickly, and accurately adjusted to a desired cutting position and then quickly and positively clamped in such position by a simple manipulative procedure.

Although I have illustrated and described preferred embodiments of the invention I do not intend to be limited to the precise details thereof as the scope of the invention is best defined in the appended claims.

I claim:

1. A rotary cutter comprising a body member having a longitudinal slot therein provided with outwardly converging walls, a cutter blade in the slot, a locking bar in the slot, means for adjustably positioning said locking bar outwardly of the slot so that one face thereof is in pressure contact with the cutter blade and the opposite face thereof is in pressure contact with an adjacent wall of the slot, said opposite face of the locking bar including a longitudinally straight and vertically convexly rounded surface in contact with said adjacent wall along a line extending longitudinally thereof, and spaced from said wall above and below this line, said locking bar being narrower at its top than at its bottom and the surface of said opposite face adjacent the top converging in an upward direction towards said one face.

2. A rotary cutter comprising a body member having a longitudinal slot therein provided with outwardly converging walls, a cutter blade in the slot, a locking bar in the slot, means for adjustably positioning said locking bar outwardly of the slot so that one face thereof is in pressure contact with the cutter blade and the opposite face thereof is in pressure contact with an adjacent wall of the slot, said opposite face of the locking bar having a convexly curved surface portion and a flat surface portion which meet along a line extending longitudinally thereof, said surface portions being in contact with said adjacent wall along their common meeting line and being spaced therefrom above and below said meeting line, said locking bar being narrower at its top than at its bottom and the surface of said opposite face adjacent the top converging in an upward direction towards said one face.
